UNITED STATES PATENT OFFICE.

GARRY J. DORMANDY, OF TROY, NEW YORK, ASSIGNOR TO UNITED SHIRT AND COLLAR COMPANY, A CORPORATION OF NEW YORK.

FOLDING-MACHINE.

1,126,421.

Specification of Letters Patent.

Patented Jan. 26, 1915.

Application filed August 16, 1913. Serial No. 785,011.

To all whom it may concern:

Be it known that I, GARRY J. DORMANDY, a citizen of the United States, residing at Troy, Rensselaer county, New York, have 5 invented certain new and useful Improvements in Folding-Machines, of which the following is a specification.

My invention relates to machines for folding and pressing blanks for collars, cuffs 10 and like articles. Its object is to fold the blanks smoothly and correctly and to press the infolded edges after this folding operation.

Particularly, the object of my invention 15 is to provide novel and advantageous means for expanding and contracting the die or templet over which the edges of the blanks are folded.

In the drawings, Figure 1 is a side elevation of a folding machine showing a preferred form of my invention; Fig. 2 is a 20 partial top plan view of the same; Fig. 3 is a front elevation of the part shown in Fig. 2; Figs. 4 and 5 are vertical transverse sections on planes 4—4 and 5—5, Figs. 3 and 25 2 respectively; Fig. 6 is a partial side elevation of the machine showing a modification.

Referring to the first five figures, 11 designates the frame or standard of the machine, provided at its right end with bearings 12 for shaft 13, Fig. 1, on which is keyed coupling member 14, adapted to clutch engagement with loose pulley 15, which may 30 be continuously driven by suitable means, as a belt, not shown. A pedal 16 is pivoted at 17 to floor brackets 18 and carries a rigid arm 19 pivotally connected by bar 20 to arm 21, the upper end of which is fast to rock- 35 shaft 22, to which is secured a forked arm 23 connected by pins 24 to the collar portion of clutch member 14. A spring 25 acts through parts 19 to 24 to normally hold 40 clutch members 14, 15 in operative relation.

45 A worm 26 on shaft 13 acts through suitable gears, cams, levers, etc., including links 27, 28, bolts 29, presser block 30, and vertically movable rod 31, to raise and lower the templet support 32, to move inward and outward the folder bars, as 33, to force said bars down toward the bed and raise them therefrom. As all these parts or their equivalents, as well as the operations performed 50 thereby, are well known in the art and form no part of the present invention, I will omit 55

any further description of them, except as may hereafter become necessary to explain the novel features of the machine.

Templet support 32 is shown as integral with rock-shaft 34, which is supported in 60 end bearings 35 at the rear of frame 11. On support 32 is bolted arm 36, at the front, free, end of which is an integral plate 37, to which is bolted head 38, comprising plate portion 39, and two longitudinal bar portions 40 connected thereto by legs 41. At one side of arm 36 is an arm 42 formed with a lateral flange 43. On arm 42 is bolted a part 44 having flange 45, which coacts with flange 43 to form cam-groove 46 shown as 65 70 having an upper portion substantially tangential to the arc of the swinging arm 36 and a lower portion at a low angle extending rearwardly therefrom. At its forward end arm 42 is secured by bolts 47 to a plate 75 48 adapted to move freely between plate 39 and bars 40. Secured to but spaced away from plate 48 is a bar 49, guided for fore and aft movement only by a transverse slot 50 in the lower faces of bars 40, in which 80 it has a sliding fit, screws 51, which hold parts 48—49 together, moving in slots 52 in transverse projections 53—54 in bars 40. Two other slots 55 cut in the lower faces of 85 bars 40 serve to hold plates 56, secured to bars 40 by screws 57, and also hold guide bars 58, to which and to bar 49 is secured by screws 59 a longitudinal bar 60, in which is cut a face groove 61 and which has at its ends top flanges 62. At the middle of bar 90 60 is secured by screw 63 a block 64, to which is in turn secured a short die-bar 65 carrying middle die-blade 66. In bar 60 at each side of block 64 are cut two slots 67, through which pass screws 68, which hold 95 in place, but permit longitudinal movement of, right and left sliding bars 69, each formed with a rear flange 70 riding in groove 61. To these bars 69 are adjustably secured by means of screws 71 riding in 100 slots 72, L-shaped die-bars 73 carrying die-blades 74, the ends of bars 73 having, in the present instance, forwardly turned portions 75 to support the ends of blades 74. Rising vertically from each bar 69 is a roller pin 105 77, which moves in a diagonal slot 78 in plate 56. Bolted to the bed 11^a, which forms the top of frame 11, is a lug 79 carrying a lateral roller pin 80, which engages in cam groove 45.

Premising that the machine as illustrated is set up for infolding blanks for the tops of collars, which require to be folded on one long side and two ends only, and that the 5 particular templet shown and the means for expanding and contracting it are adapted to this operation, the operation is as follows: The machine standing in its "stopped" position, as shown in Fig. 1, the 10 operator places a blank, ordinarily consisting of two superposed plies of fabric, on bed 11^a in proper relation to templet blades 66—74. He then starts the machine by 15 tilting pedal 16, which acts through parts 19 to 24 to engage clutch members 14—15. At this time the templet is in its non-operative, contracted position, shown in dotted lines, Fig. 2, that is, the outer blades 74 are 20 drawn forwardly and inwardly from their normal position. The machine is timed so that the templet support 32 and all the parts connected therewith are first drawn downward by rod 31 toward bed 11^a. During 25 the first part of this movement the inclined lower portion of cam groove 46 rides on pin 80 whereby arm 42 and its connected parts are moved rearwardly on arm 36, thereby causing pins 77 to move toward the outer ends of inclined slots 78 and expanding the 30 templet to the position shown in full lines Fig. 2 and in Fig. 3 before the templet reaches its operative position on the blank resting on bed 11^a. A further rotation of shaft 13 causes the movement of the infolder 35 blades inward over the templet blades in the usual manner, whereby the edges of the blank are folded, after which presser blocks 30 are forced downward upon the folder blades while these are in their inward position 40 to press and dry the folder edges of the blank on the heated bed. Next, the presser blocks are raised, the folder blades are drawn outward and finally, the templet is raised from the bed, carrying the folded 45 blank. During the latter part of this upward movement of the templet the pin 80 passes through the lower inclined portion of groove 46, forcing arm 42 forward and thus contracting the templet. The machine 50 is then stopped, preferably automatically, when a second similar cycle of operations is begun.

In the obvious modification of the machine shown in Fig. 6, arm 82 is the analogue of arm 42 of the first construction, carries at its forward end the same or equivalent die expanding and contracting means, and differs therefrom only in the 55 means at its rear end by which its longitudinal movement is effected. At its downwardly curved rear end 83 is a laterally projecting roller pin 84 moving in a cam groove 85 in a lug 86 secured as before to the bed 11^a of the machine. Groove 85 has 60 its upper portion at an angle with the tan-

gent to the arc in which arms 36 swings, and its lower portion curved to a segment of that arc. Obviously, the operation of the device will be unchanged, in that the initial downward movement of the arm will 70 act to expand the templet, so that it will come down on the blank in expanded position, and that the later portion of its upward movement will contract the die or templet as before, whereby any tendency to either stretch or crumple the blank is 75 avoided.

The present invention is an improvement over that of my pending application filed 80 January 24, 1913, which has received Serial Number 743,982, in that it provides the simple and effective means shown for automatically expanding and contracting the templet during the time of its movement toward and from the bed. This automatic movement of the die blades during their 85 bodily movement shortens the time required for a cycle of the machine, or allows a greater time for the pressing operation in a 90 cycle of given length.

The means shown are simple, strong and, 95 being above the bed of the machine and in plain sight of the operator, cannot work loose or get out of order without immediate detection.

It will be understood that the number or 100 position of the die blades, either stationary or movable, or the particular connecting parts between the moving arm and these blades, is immaterial to my invention.

What I claim is:

1. In a folding machine, a bed; a contractible templet; an arm on which said templet is mounted for movement toward and from said bed; mechanical means including a power shaft and operative connections between said shaft and said arm for moving the latter; and means for expanding said templet during the earlier portion only of its movement toward said bed and for contracting it during the later portion only of its movement from said bed, whereby said templet is brought down upon a blank on said bed in its fully expanded condition and is raised from said bed carrying a folded blank also in its fully expanded condition.

2. In a folding machine, a bed; a contractible templet; an arm on which said templet is mounted for movement toward and from said bed; mechanical means including a power shaft and operative connections between said shaft and said arm for moving the latter; and means for expanding said templet during the earlier portion only of its movement toward said bed and for contracting it during its movement from said bed, whereby said templet is brought down upon a blank on said bed in its fully expanded condition.

3. In a folding machine, a bed; a contractible templet; an arm on which said templet is mounted for movement toward and from said bed; mechanical means including a power shaft and operative connections between said shaft and said arm for moving the latter; and means for expanding said templet during its movement toward said bed and for contracting it during the later portion only of its movement from said bed, whereby said templet is raised from said bed in its fully expanded condition and carrying a folded blank.
4. In a folding machine, a bed; a contractible templet; means for moving said templet toward and from said bed; and means automatically operative with said moving means for expanding said templet simultaneously with the earlier portion only of its movement toward said bed and for contracting it simultaneously with its movement from said bed, whereby said templet is brought down upon a blank on said bed in its fully expanded condition.
5. In a folding machine, a bed; a contractible templet; means for moving said templet toward and from said bed; and means automatically operative with said moving means for expanding said templet simultaneously with its movement toward said bed and for contracting it simultaneously with the later portion only of its movement from said bed whereby said templet is raised from said bed in its fully expanded condition and carrying a folded blank.
6. In a folding machine, a bed, a contractible templet; a swinging arm on which said templet is mounted for movement toward and from said bed; mechanical means in-
- cluding a power shaft and operative connections between said shaft and said arm for moving the latter; and two coöperative parts, one of which is movable with and upon said arm and the other of which is secured to an immovable part of the machine for expanding and contracting said templet simultaneously with the movement of said arm.
7. In a folding machine, a bed; a contractible templet; a swinging arm on which said templet is mounted for movement toward and from said bed; mechanical means including a power shaft and operative connections between said shaft and said arm for moving the latter; and two coöperative parts, one of which is movable with and upon said arm and the other of which is stationary, said parts being provided respectively with cam and pin engaging means, for expanding and contracting said templet simultaneously with the movement of said arm.
8. In a folding machine, a bed; a contractible templet; a swinging arm on which said templet is mounted for movement toward and from said bed; mechanical means including a power shaft and operative connections between said shaft and said arm for moving the latter; and two coöperative parts having cam and pin engagement with each other for automatically expanding said templet during its initial movement toward said bed and contracting it during the later portion of its movement from said bed.
